UNITED STATES PATENT OFFICE.

HEINRICH HOFMANN, OF MOUNT CLEMENS, MICHIGAN.

DESIGN FOR A WIRE BASKET.

SPECIFICATION forming part of Design No. 30,979, dated June 13, 1899.

Application filed May 20, 1899. Serial No. 717,668. Term of patent 14 years.

To all whom it may concern.

Be it known that I, HEINRICH HOFMANN, a citizen of the United States of America, residing at Mount Clemens, in the county of Macomb and State of Michigan, have invented and produced a new and original Design for a Wire Basket Particularly Designed for Culinary Purposes, of which the following is a specification, reference being had therein to the accompanying drawing, forming part thereof, and in which my new design is shown in elevation.

As shown in the drawing, the leading or material feature of my design consists in the spheroidal-shaped body A, formed of a series of vertical stay-wires a, connected by horizontal tie-wires B. At the mouth and at the

base of the body the ends of the stay-wires are bent around the tie-wires and collectively form the roll-like ornamental borders C C. 20 The body is set upon a short cylindrical imperforate base D and has attached to the mouth the rigid wire handle E.

Having described my invention, what I claim as new, and desire to secure by Letters 25 Patent, is—

The design for a wire basket as herein shown and described.

In testimony whereof I affix my signature in presence of two witnesses.

HEINRICH HOFMANN.

Witnesses:

OTTO F. BARTHEL,
V. D. KINNER.
